Marsteller, Attorney.

UNITED STATES PATENT OFFICE.

WILLIAM M. THOMAS, OF ALBUQUERQUE, NEW MEXICO.

MIXING DEVICE.

1,193,085.

Specification of Letters Patent.

Patented Aug. 1, 1916.

Original application filed June 29, 1915, Serial No. 37,054. Divided and this application filed December 14, 1915. Serial No. 66,759.

To all whom it may concern:

Be it known that I, WILLIAM M. THOMAS, a citizen of the United States, residing at Albuquerque, in the county of Bernalillo 5 and State of New Mexico, have invented certain new and useful Improvements in Mixing Devices, of which the following is a specification.

My present invention relates to new and 10 useful improvements in mixing devices for internal combustion engines, being a division of my copending application for moisture supplying attachments for internal combustion engines, filed by me June 29, 15 1915, and bearing the Serial No. 37,054.

The primary object of my present invention is the provision of an improved mixer through which vapor or steam is supplied to the explosive mixture as it passes from 20 the carbureter to the intake manifold of the engine.

In this connection, my invention comprehends a mixing device adapted to be inserted between a carbureter and intake 25 manifold and adapted for connection with any suitable source of vapor or steam, the device being so arranged as to mix vapor with the explosive mixture coming from the carbureter.

With these and other objects in view, my 30 invention will be more fully described, illustrated in the accompanying drawings, and then specifically pointed out in the claims which are attached to and form a part of this application.

In the drawings: Figure 1 is a side elevational view of a conventional form of internal combustion engine, showing my invention applied thereto; Fig. 2 is a vertical 35 sectional view taken through the mixing device; Fig. 3 is a section on the line 3—3 of Fig. 2; Fig. 4 is a perspective view of the various parts of the mixing device in unassembled position.

Corresponding and like parts are referred to in the following description and indicated in all the views of the drawings by the same reference characters.

My improved mixing device may be constructed as a part of the carbureter proper, as a part of the intake manifold of an internal combustion engine, or as an independent and detachable unit adapted to be interposed between the carbureter and mani-

fold, the latter being the preferred method of construction.

The device includes a body portion 10, formed of metal or other suitable material and preferably either elliptical or rhombic shaped in plan view to correspond in general outline to the outline of the flanges 11 and 12 of the carbureter 13 and intake manifold 14, respectively, between which it is to be connected. For this purpose, it is provided adjacent its ends with bolt receiving bores by means of which bolts 15 may be applied to secure it in place, metallic gaskets or packing rings being usually interposed between its faces and the flanges of the manifold and carbureter. This body 70 member is provided centrally with a gas opening or passage 16 substantially equal in diameter to the internal diameter of the outlet passage of the carbureter and the intake passage of the manifold and so disposed with respect to the bolt receiving openings as to extend in alignment with such passages and in effect form a continuation of them. As best shown in Figs. 2 and 4 of the drawings, this passage, at its outlet end, is somewhat enlarged to provide a stop shoulder 17, for a reason which will be later explained, and the passage, intermediate its length, is recessed or cut-away to form an annular chamber 18, completely surrounding it. The side wall of the body 10 is provided with a passage 19 communicating with the chamber 18 and tapped at its outer end to receive the threaded end of a pipe 20 leading to a manually operable cut-off cock 21.

A metallic ring or sleeve 22 fits closely within the passage 16 and closes the chamber 18, forming a wall therefor. This ring is provided at diametrically opposite points 95 with openings to receive the ends of pipes or tubes 23 which, as a result, extend diametrically across the passage 16, these pipes, where they cross each other, being either bent out of the way for that purpose or 100 fitted together in any suitable manner. That face of each pipe or tube which is directed toward the outlet end of the passage 16 is provided with a series of perforations 24 through which any vapor or steam admitted to the chamber 18 may be drawn by suction of the engine. In order to thoroughly mix the explosive mixture supplied

from the carbureter with the steam supplied from the chamber 18, I provide a screen 25 of any suitable foraminous material, preferably fine wire gauze, which screen is generally reinforced peripherally by a metallic ring 26, the peripheral edge of the screen and ring seating against the shoulder 17, as best shown in Fig. 2.

A pipe 27 leads from the inlet port of the 10 cut-off cock 21 to a vaporizing cup 29 which is connected by a pipe 30 to the cooling jacket of the engine, the pipe 30 being threaded or otherwise inserted in an opening formed in the water jacketing of the 15 engine.

The specific construction and operation of 20 this vaporizing cup is fully set forth in my copending application previously referred to and need not be described in this case. It should, however, be noted that a constant 25 water level is maintained in the vaporizing cup and that, due to the close proximity of the cup to the engine, the small amount of water contained therein will be heated to generate steam or vapor which may be drawn off to the mixer and so to the engine cylinders.

In operation, the cut-off cock 21 is opened 30 to any suitable extent dependent upon the amount of steam which the operator desires to supply to the engine manifold and the engine is then driven in the usual manner. The steam drawn from the vaporizing cup passes into the chamber 18 of the mixer and 35 from this chamber through the perforated pipes or tubes 23 into the gas passage 16 and so, together with the explosive mixture from the carbureter, through the screen 25 to the manifold 14 and from the manifold 40 to the engine cylinders.

By providing means for adding and thoroughly mixing the steam with the explosive mixture from the carbureter, I prevent the formation of carbon in the motor and upon 45 the spark plugs and also increase the life of lubricating oil used in the cylinders and valves. As a result, the motor is smoother running and more powerful than would otherwise be the case.

Having thus described the invention, what 50 is claimed as new is:

1. A moisture supplying device and mixer adapted to be inserted between a carbureter

and intake manifold and including a body having a fuel passage and an annular chamber surrounding the passage, a ring fitting in the passage and forming a wall for the chamber, perforated tubes extending across the ring and communicating at their ends with the chamber, and a mixing screen 60 mounted in the outlet end of the fuel passage, the body being formed with an inlet opening communicating with the chamber. 55

2. A moisture supplying device and mixer adapted to be inserted between a carbureter 65 and intake manifold and including a body having a fuel passage and an annular chamber surrounding the passage, perforated tubes extending across the passage and communicating at their ends with the chamber, 70 and means providing for passage of moisture to the chamber.

3. A moisture supplying device and mixer adapted to be inserted between a carbureter and intake manifold and including a body 75 formed with a fuel passage, a screen extending across the outlet end of the passage, perforated tubes extending across the passage between the inlet end thereof and the screen, and means for supplying moisture to the 80 tubes.

4. A moisture supplying device and mixer adapted to be inserted between a carbureter and intake manifold and including a body having a fuel passage and an annular chamber 85 surrounding the passage, a tube extending across the passage and communicating at its ends with the chamber, said tube having perforations formed in that side directed toward the outlet end of the passage, and means for supplying moisture to the chamber. 90

5. A moisture supplying device and mixer adapted for application to a carbureter and including a body having a fuel passage 95 and a chamber surrounding the passage, a perforated tube extending across the passage and communicating at its ends with the chamber, and means providing for passage of moisture to the chamber. 100

In testimony whereof, I affix my signature.

WILLIAM M. THOMAS. [L.S.]

Witness:

A. W. GOODRICH.
